US0D1112700S

(12) **United States Design Patent** (10) **Patent No.:** **US D1,112,700 S**
(45) **Date of Patent:** **** Feb. 10, 2026**

(54) **STROLLER FAN**

(71) Applicant: **Shenzhen Keeway Technology Co., Ltd.**, Shenzhen (CN)

(72) Inventor: **Guoqiang Bao**, Shenzhen (CN)

(73) Assignee: **Shenzhen Keeway Technology Co., Ltd.**, Shenzhen (CN)

(**) Term: **15 Years**

(21) Appl. No.: **29/980,248**

(22) Filed: **Dec. 23, 2024**

(30) **Foreign Application Priority Data**

Aug. 23, 2024 (CN) 202430537059.9

(57) **CLAIM**

The ornamental design for a stroller fan, as shown and described.

DESCRIPTION

FIG. 1 is a front, right side and top perspective view of a stroller fan showing my new design;

FIG. 2 is a rear, left side and bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The dash-dash broken lines in the drawings depict the portions of the stroller fan that form no part of the claimed design.

1 Claim, 8 Drawing Sheets
